William F. Menewisch, Philadelphia, Pa., assignor to E. L. Mansure Co., Chicago, Ill., a corporation of Illinois

Application July 18, 1936, Serial No. 63,927

Term of patent 7 years

To all whom it may concern:

Be it known that I, William F. Menewisch, a citizen of the United States, residing at Philadelphia, in the county of Philadelphia and Commonwealth of Pennsylvania, have invented a new, original, and ornamental Design for a Textile Fabric, of which the following is a specification, reference being had to the accompanying drawing, forming a part thereof.

The figure is a plan view of the textile fabric embodying the design of this invention.

I claim:

The ornamental design for a textile fabric, as shown.

WILLIAM F. MENEWISCH.
